KNITTED FABRIC AND METHOD OF MAKING
ITEugene M. Zesch, Reading, Pa., assignor to Karl
Lieberknecht, Inc., a corporation of Pennsyl-
vania

Application May 6, 1940, Serial No. 333,544

16 Claims. (Cl. 66—173)

My invention relates to knitted fabrics and to methods of making them, and particularly to fabrics and methods whereby the loops in the first courses, as in the welts of stockings or full fashioned stocking blanks, are prevented from unravelling at the selvedges where the yarn is cut.

In knitting a fabric of the above-indicated character, loops of the first course are maintained under tension between the needles of a knitting mechanism and the hooks of a take-off device or welt bar of the machine, and so maintained until the welt is turned and these loops topped onto the loops at the welt line. Such loops, at the beginning of the first course or selvedge where the yarn is cut, frequently give trouble by unravelling, which opens up the course during subsequent handling, such as topping, looping and seaming.

Particularly where the take off is effected in a manner reducing the interloop friction, as by engagement of the welt hooks only with every other sinker and divider loop, this unravelling is likely to occur, because of the reduced friction or locking action between the loops of the first and second courses resulting from the reduced number and increased course-wise widths of the loops of the first course.

Also, the unravelling of the loops of the first course is effected more or less according to the shapes and sizes of the loops, the relation of the loops to each other, and the character of the yarn as to diameter, number of threads, texture, such as surface smoothness, and other factors, so that the tendency of the first course to unravel may be greater or less according to any one or combination of the above-mentioned causes.

To ensure against unravelling of the loops of the first course of a fabric of any number of yarns of the nature stated, particularly in running very smooth yarns as of artificial silk or other synthetic yarn which, because of the slick surfaces, are more easily unravelled than silk or cotton yarns having relatively rough surfaces, it is accordingly, among the objects of this invention to lock each such course at its beginning, as by intertwining a short length or preliminary extension of the yarn with a corresponding length of the course, and knitting this increased-strand section of the course to the second course, or by equivalently locking the yarn to, or burying it in, the fabric.

Another object of the invention is specifically to effect such locking in an instance where the fabric is so formed for taking from the needles

that the ordinary friction or locking tendency between the loops of the first and second courses is reduced or altered.

Another object of the invention is to produce a knitted fabric of the above-indicated character, as in a stocking, particularly in a full fashioned stocking blank, that shall be simple and durable in construction, economical to manufacture, and effective in service.

A further object of the invention is to provide a method that shall expedite the attainment of the above-mentioned results without substantial change in the general duties of an operator, or in the construction and operation of the machine, except to facilitate such duties and operation in the production of a better fabric, and to avoid trouble, expense and loss of time and material.

With such objects in view, as well as other advantages which may be incident to a utilization of the improvements, the invention comprises the elements and combinations thereof hereinafter set forth and claimed, with the understanding that the several necessary elements constituting the same may be varied in proportion, arrangement and texture, without departing from the spirit and scope of the invention as intended, and as set forth in the drawings, specification and claims.

In practicing the invention in a full fashioned stocking blank, and during its production on a machine for this purpose, in each of the examples of single yarn welts given, at the end of the next previous set, the machine is stopped, with the couloring on the left side, as viewed from the front, and all friction boxes disengaged from the friction rod.

The welt yarn carrier rod, which may be standing on either the right or left side, is positioned manually against, and to the right of, an intermediate stop, this operation positioning the carrier a distance, such as a half inch, to the left of the right side of the sinker head. The welt carrier rod is then locked to its friction box, the machine started and, as the couloring takes place from left to right, the welt yarn is kinked around the needles for the above-mentioned distance at the right side selvedge.

With the intermediate stop lifted, the first true welt course is then started, laid and formed into loops, with a half inch of the loops at the right side selvedge coincident, or in register, with the kinks or loops of the above-mentioned distance or extension, thus rendering the latter a part of the first actual course which is thereby of multi-

strand thickness or of greater thickness through this half inch than the remainder of the course. When interknitted simultaneously with the yarn of the first course to the yarn of the second course, the half inch extension or length becomes intertwined with the yarns of both courses, thereby locking the yarn against slippage and unravelling.

In case the welt carrier is standing at the left side of the machine, at the end of the next previous set, it is manually pushed across the head to the right side, a bevelled dog on the carrier rod lifting a spring-biased pin of the above-mentioned intermediate stop, thereby permitting the rod to pass underneath this stop. The operator then immediately reverses the motion of the welt carrier rod and brings it across this stop, which is forced to the low position by the spring and an auxiliary control lever to be hereinafter set forth.

Knitting is continued to welt line loops, onto certain of which, after turning the welt, loops of the above-mentioned first course and the extension are topped, thus further locking the course.

In order to render the invention more clearly understood, means are shown in the accompanying drawings for carrying the same into practical effect, without limiting the improvements in the useful applications thereof to the particular constructions and steps which, for the purpose of explanation, are made the subject of illustration.

In the drawings:

Figure 1 is a loop diagram of a portion of the welt fabric of a full fashioned stocking blank constructed in accordance with the invention, and having its first course adapted for topping onto alternate needles at the welt line;

Fig. 2 is a diagram, similar to Fig. 1, of a corresponding knitted welt portion having loops of a first course for topping onto all the needles corresponding to the width of the portion at the welt line;

Fig. 3 is a diagrammatic perspective view of parts of a full fashioned knitting machine on which the fabric of the invention may be produced by the novel method; and

Fig. 4 is a diagram in perspective, illustrating certain elements at a stage of the action of topping a first course of the fabric onto the needles at the welt line.

Referring to Fig. 1, the fabric or welt, in this instance, is constructed from a single yarn having a starting end 1 disposed a distance A from the right end of a first course 8 of loops, as viewed in the drawings. The distance A may be any selected extent, such as the above-mentioned half inch.

From the end 1, the yarn forms loops B to the right end of the course 8, at which it turns, through a bight 9, and forms loops C extending along the loops B and beyond the latter to the left end of the course 8. Thus, although disposed at the beginning of the first course 8, the yarn of the loops B in this case is actually an extension of the main body of yarn of this course laid therewith to form a single course of double strand thickness for a portion of its length through the distance A, and of single strand thickness for the remainder of its length. In this relation alone, the loops B and C have frictional locking interpositioning with each other.

From the left end of the first course 8, the yarn continues through loops D of a second course 10 that is interknitted with the loops B and C to add to the frictional holding and lock-

ing effect tending to prevent unravelling of the first course.

Knitting is continued, through a body 12 of the fabric, to form loops along a welt line, to be hereinafter further pointed out, onto alternate loops of which the loops B and C are topped, and knitted to the leg body of the stocking fabric.

In forming the first full or complete course 8, according to the fabric being knitted, the yarn is originally formed into loops about all the knitting machine needles corresponding to such length, but has only the alternate of its sinker and divider loops in the length taken off by the welt hooks, so that the intermediate needle loops are dropped, and the course formed with only half the number of needle loops to facilitate the above-mentioned topping. This construction in ordinary practice before the invention hereof in which the loops B are provided, reduced the normal frictional locking of the yarn of the first course, and rendered unravelling of loops corresponding to the loops C more likely to occur.

In the form of the invention shown in Fig. 2, in which corresponding elements are designated by corresponding reference characters each having the suffix a, the fabric is also constructed from a single yarn having a starting end 1a disposed a distance Aa from the right end of a first course 8a of loops. From the end 1a, the yarn forms loops Ba to the right end of the course 8a, at which it turns through a bight 9a, and forms loops Ca extending along the loops Ba and beyond the latter to the left end of the course 8a.

From the left end of the course 8a, the yarn continues through loops Da of a second course 10a that is interknitted with the loops Ba and Ca, and further extends through a body 12a of the fabric to form loops along a welt line, as above set forth.

In this form, the yarn of the first and subsequent courses is formed about successive needles, and taken off by a welt bar having a hook for each sinker and divider loop; the invention in this case also preventing the unravelling of the first course loops, as above set forth.

Referring to Fig. 3, a knitting machine set up for producing the fabrics of Figs. 1 and 2, includes a needle bank 14, which may be the bank of a single section machine, but which is one of several banks of a multi-section machine, as indicated.

A yarn carrier or finger 15 is mounted on a carrier rod 16 operating between left and right end stops 17 and 18, respectively, and carrying a dog 20 for releasable locking cooperation with a lever 21 on a friction box 22.

The box 22, mounted on a friction rod 25, carries a shaft 26 by which the lever 21 is pivotally mounted, and has portions 27 for bracing the lever 21 against side thrust incident to driving the rod 16 through the dog 20.

A bevelled dog 29, fixed to the carrier rod 16, supports an adjustable contact element in the form of a screw 31 for engagement, under certain conditions, with a spring plunger stop 32 mounted in a stationary member 33. A spring 34 normally biases the plunger stop 32 upwardly, out of the way of the dog 29 and its contact screw 31, and another spring (not shown) inside the spring 34 is actuated by a plunger pin 35 to bias the stop 32 downwardly when a lever 36 depresses the pin 35 to place the stop in the path of movement of the dog 29; the arrangement being such that, in its low position, the stop 32 may be raised by the bevel of the dog 29 even though the stop

is held in its low position by the lever 36. The latter is pivotally mounted on a pin 37, and has a cam follower portion 38 for cooperation with a cam 39 having a high spot 42 and mounted on a pattern control shaft 43 which is auxiliary to, and controlled by, a usual main pattern chain (not shown).

In Fig. 4, are indicated the needle bank 14, the completed fabric body 12, in the form of a partially turned welt, a take-off rod 45, and flexible elements 46 for connection to a usual take-off reel.

In operation, as heretofore suggested, at the end of the previous set or complete knitting cycle, the machine is stopped, in this instance with the coulisse at the left side, and the friction boxes, including the box 22, disconnected from the friction rod 28.

The welt carrier rod 16, which may be standing at either the right or left side of the knitting field, in contact with either the stop 18 or the stop 17, respectively, is positioned manually, in this instance, with the contact screw 31 against the intermediate plunger stop 32, which positions the rod 16, by the distance A, to the left of the right end of its stroke.

When the carrier rod 16 and the carrier finger 15 are in this position, as illustrated in Fig. 3, the friction box 22 is locked to the friction rod 28, the machine is started, and the welt yarn is laid from left to right, and kinked around the needles in the distance A at the right side selvage.

The first true or full course is then laid by bending the yarn through the bight B, as shown in Fig. 1, and moving the carrier rod 16 from right to left against the end stop 17, during and following which action, the loops B and C are formed, and subsequently interknitted to the loops D of the second course 10.

Knitting is continued to complete the welt body 12 and form loops therein at a welt line 50, as indicated in Fig. 4, at which stage, the loops B and C are topped onto the needles 14, with the welt line loops, and knitting extended in a usual manner.

If, at the end of the previous set, the welt carrier rod 16 is standing at the left end of its stroke against the end stop 17, it is manually pushed to the right end, the bevelled dog 29 lifting the plunger stop 32, thereby permitting the dog to pass this stop and to be returned to position against the same, after which, and before running the first full course, the high spot 42 of the cam 39 rides off the follower 38, whereby the spring 34 lifts the intermediate stop out of the path of the dog 29.

I claim as my invention:

1. A knitted fabric comprising an extension of the yarn of the fabric at the beginning of the first course turned inwardly and locked in position therealong.

2. A knitted fabric comprising an extension of the yarn of the first course at the beginning thereof turned inwardly therealong and having loops knitted with loops thereof to loops of the second course.

3. A knitted fabric comprising an extension of the yarn thereof at the beginning of the first course turned inwardly therealong and having loops knitted with loops thereof to loops of the second course, next adjacent needle loops of said first course and extension being in alternate needle wales of the fabric.

4. A knitted fabric comprising first and sec-

ond courses of different numbers of loops, respectively, and an extension of the yarn of the fabric at the beginning of the first course turned inwardly therealong and having loops knitted with loops thereof to loops of the second course.

5. A flat knitted fabric comprising a first course yarn including a full length section and short length section lying along the full length section at the beginning thereof, next adjacent loops of said yarn being disposed in alternate needle wales of the fabric.

6. The method of making a knitted fabric, which comprises laying to a needle bank of a knitting machine an extension of the yarn of the first course at the beginning thereof opposite to the direction of laying the yarn of the course from a point inwardly along the bank to the first needle by moving the yarn carrier against an intermediate stop, moving the carrier to the beginning of the first course, raising the stop, reversing the movement of the carrier to lay the yarn of the first course, forming the yarn of the extension and first course into loops, inserting the hooks of a welt bar into certain of said loops, laying and forming into loops the yarns of the second course, interknitting loops of the second course with loops of the first course and its said extension, continuing knitting to the loops at the welt line, turning the welt, and topping said first course and said extension onto certain of said welt line loops.

7. The method of making a knitted fabric, which comprises laying to a needle bank of a knitting machine an extension of the yarn of the first course at the beginning thereof opposite to the direction of laying the yarn of the course from a point inwardly along the bank to the first needle by moving the yarn carrier free from the friction rod against an intermediate stop, locking the carrier through its friction box to said rod, actuating the rod to move the box to the beginning of the first course, raising the stop, reversing the movement of the rod to lay the yarn of the first course, forming the yarn of the extension and first course into loops, inserting the hooks of a welt bar into certain of said loops, laying and forming into loops the yarn of the second course, interknitting loops of the second course with loops of the first course and its said extension, continuing knitting to the loops of the welt line, turning the welt, and topping said first course and said extension onto certain of said welt line loops.

8. The method of making a knitted fabric having a welt, which comprises laying to a needle bank of a knitting machine an extension of the yarn of the first course at the beginning thereof opposite to the direction of laying the yarn of the course from a point inwardly along the bank to the first needle by moving the yarn carrier free from the friction rod against an intermediate stop, locking the carrier through its friction box to said rod, actuating the rod to move the box to the beginning of the first course, raising the stop, reversing the movement of the rod to lay the yarn of the first course, forming the yarn of the extension and first course into loops, inserting next successive hooks of a welt bar into alternate sinker and divider loops of the first course including said extension, laying and forming into loops the yarn of the second course, interknitting loops of the second course with loops of the first course and its said extension, continuing knitting to the loops at the welt line, turning the welt, and topping said first

course and said extension onto certain of said welt line loops.

9. The method of making a flat knitted fabric, which comprises the production of a single full length course including the operations of return laying the yarn of the course on itself for a distance less than said full length and continuing the laying of the yarn to complete the course, laying the yarn of another course, and interknitting said courses to each other.

10. A knitted fabric comprising a welt having its first course of loops topped onto loops of the welt line, and an extension of the yarn of the first course at the beginning thereof turned inwardly and locked in position therealong.

11. A knitted fabric comprising a welt having its first course of loops topped onto loops of the welt line and an extension of the yarn of said course at the beginning thereof turned inwardly and locked in position therealong, next adjacent needle loops of said first course and extension being in alternate needle wales of the welt.

12. The method of making a flat knitted fabric, which comprises laying a short length of the yarn of the first course from a position inwardly along the course to position at the beginning thereof, laying a full length of said yarn from the latter position, and knitting said lengths to the yarn of the second course.

13. The method of making a flat knitted fabric, which comprises laying a short length strand of the first course from a position inwardly along the course to position at the beginning of the course, oppositely laying a full length strand, and knitting said short and full length strands to the yarn of the second course with next adjacent needle loops in alternate needle wales of the fabric.

14. The method of making a knitted fabric having a welt, which comprises laying a short length of the yarn of the first course of the welt from a position inwardly along the course

to a position at the beginning of the course, laying a full length strand of said yarn, knitting said lengths to the yarn of the second course, continuing knitting to the loops at a welt line, turning the welt, and topping said first course including said extension onto certain of said welt line loops.

15. The method of making a full fashioned stocking blank welt, which comprises laying 10 yarn to a needle bank of a full fashion knitting machine including the laying of a short length of the yarn of the first course from a position inwardly along the bank to the first needle and a full course length of the yarn of said course along the bank from the first needle, forming said lengths into loops, inserting the hooks of a welt bar into certain of said loops, laying and forming into loops the yarn of the second course, inter-knitting loops of the 20 second course with loops of said lengths, continuing knitting to the loops at a welt line, turning the welt, and topping said first course including said lengths onto certain of said welt line loops.

16. The method of making a knitted fabric having a welt, which comprises laying to a needle bank of a knitting machine an extension of the yarn of the first course from a position inwardly therealong to a position at the beginning thereof, laying a full length of said yarn from the latter position, forming the extension and the full length into loops, inserting the hooks of a welt bar into certain of said loops, laying and forming into loops the yarn of the 30 second course, inter-knitting loops of the second course with loops of the first course and said extension, continuing knitting to the loops at the welt line, turning the welt, and topping said first course and said extension onto certain of said 40 welt line loops.

EUGENE M. ZESCH.
